BOILER FEED WATER SUPPLY SYSTEM

Harry D. Forse, Anderson, Ind.

Application March 7, 1940, Serial No. 322,703

13 Claims. (Cl. 122—456)

This invention relates to a method of and apparatus for supplying water to a boiler for steam generation thereby, which steam may be utilized as for example, expended by pressing machines as distinguished from a closed system steam arrangement wherein the steam after doing the work intended, condenses and returns to the boiler.

The problem, therefore, in a boiler system intended for the specific use mentioned by way of example only, is one wherein there must be supplied water for steam generation and not water merely for "make-up" purposes. This type of system requires the quite frequent supply of water to the boiler and for small pressing plant installations, the boiler and steam generating system must be arranged for economical operation to generate rapidly a relatively small amount of steam and, therefore, it is uneconomical to generate a large volume of steam for possible use, such large volume necessitating a large boiler capacity.

The chief object of this invention is to supply water for steam generation to a steam generating boiler of limited capacity and in a controlled manner so that steam may be economically generated.

The chief feature of the invention consists in supplying water to a reservoir and from the reservoir supplying the water as required to the boiler, the water in the reservoir being preheated and the reservoir and boiler being so connected that the water may be supplied to the boiler by gravity by reason of the balancing of boiler pressure on the reservoir containing the water during the supplying interval to the boiler.

Another and equally important feature is the automatic control of the water supply to the reservoir and the communications between that reservoir and the boiler.

Another feature of the invention consists in reducing the effectiveness of boiler pressure on the reservoir during the interval the water is supplied thereto, and this likewise is automatically effected.

Other objects and features of the invention will be set forth more fully hereinafter.

The full nature of the invention will be understood from the accompanying drawings and the following description and claims:

In the drawings, Fig. 1 is a diagrammatic elevation of one embodiment of the invention showing the same with apparatus capable of manual operation as well as automatic operation.

Fig. 2 is a diagrammatic plan view of a me-

chanical type header structure, wherein all the control valves are incorporated.

Fig. 3 is a diagrammatic elevational view of a control or cam shaft for cyclic control associated with one of the normally closed valves, the cam operation being of indirect character by means of an interposed rocker arm.

Fig. 4 is a diagrammatic time chart of the operation of the several control valves, the full lines indicating one method of operation and the dotted lines indicating a second method of operation.

Fig. 5 is a wiring diagram of a solenoid operable valve arrangement of the drum controller type of valve control.

Fig. 6 is a side elevation of the header and electro valve.

Fig. 7 is a side elevation of "holding" switch control.

Fig. 8 is a similar view of a modified form thereof.

Fig. 9 is an enlarged view of a modified form of float operable switch.

In Fig. 1 of the drawings, 10 indicates a conventional boiler arrangement provided with a gauge 11 and a steam outlet and supply line 12 controlled by a valve 13 by which steam may be utilized for pressing and like machines. The numeral 14 indicates the normal water level in this conventional boiler and the float 15 actuates a switch member 16 so that it engages a contact 17 to close a circuit between lines 18 and 19 to a motor, not shown, the same being the control element for supplying water to the boiler.

Associated with the boiler is a fuel supply line 20 controlled by a valve 21 and having burner arrangement 22 for heating the water to form steam in said boiler and under pressure. The boiler, if desired, may be provided with a clean-out drain structure 23 controlled by valve 24. The boiler also may be provided with a water glass construction 25. The boiler includes a pressure discharge line 26 and a water supply line 27, the former discharging from that portion 45 of the boiler not including the water but the steam and herein from the top of said boiler and the latter discharging to the water containing portion of the boiler and herein to the bottom thereof.

There is provided a reservoir 28 and the same may include a drain 29 controlled by the valve 30. This is for dirt collection and removal. The line 26 communicates with the top of the reservoir 28 as at 31. The boiler water supply line 27 communicates with the reservoir 28 at the

bottom of the latter, as indicated at 32. The reservoir is supplied by a pressure line 33 and the latter preferably communicates with the reservoir near the bottom thereof. The reservoir is provided, if desired, with water glass gauge structure 34. The reservoir also is provided with a vent pipe 35 leading from the top of the reservoir.

The line 26 which connects, as herein illustrated, the top of the boiler to the top of the reservoir, includes a manually adjustable regulating valve 36 and a valve 37 which is of quick opening and quick closing type. Valve 36 is provided for regulation only while the valve 37 is provided for control purposes hereinafter more specifically to be pointed out.

The line 27 between the boiler and the reservoir and connected to the bottoms of both, includes a regulating valve 38 and a quick opening and quick closing valve 39, the functions of which are substantially the same as the valves 36 and 37, previously mentioned.

The pressure supply line 33 includes the regulating valve 40 and the quick opening and quick closing valve 41. The vent line in a like manner, is provided with the regulating valve 42 and the quick opening and quick closing valve 43.

When close regulation is not desired, it is quite apparent that the valves 36, 38, 40 and 42 may be omitted and the several lines, reduced to the desired diameters, then will accomplish the same function. However, to adjust the present invention to the steam pressure operable and/or steam consuming device, or devices, these valves have value although after adjustment they require no further attention and have no cyclic control which is the function of the valves 37, 39, 41 and 43.

For an understanding of the broad phase of the invention, it is to be understood that the valve 41 is opened to fill the reservoir with water to the desired degree. Valve 41 is then closed. Thereafter the valve 38 is opened to permit water to discharge by way of line 27 to the boiler. When the required amount of water is in the boiler, the valve 38 is closed. Then the valve 43 is opened to vent the reservoir to permit water to be supplied by line 33 to the same through the valve 41 when opened. The valves 43 and 41 may be closed simultaneously.

During the following interval and during the interval that water was being supplied to the auxiliary reservoir, the valve 38 is closed as well as the valve 37 and the heat source 22 generates steam which is under pressure in the boiler 10. This steam then is applied, by reason of the fact the valve 37 is then opened to the reservoir 28, and serves to preheat the water therein. To prevent release of pressure and escape of steam, vent controlling valve 43 is closed at this time. When steam is drawn from the boiler through line 12, the water level lowers as the steam is generated and withdrawn and when the desired lower level has been reached, the valve 38 is opened and water is supplied to the boiler. Valve 37 during this water supply period is still open so that there is a balance of pressure on the water in the reservoir 28 which pressure is created by the boiler so that the water in the reservoir 28 can flow by gravity, assisted by pressure on the top thereof to the boiler 10.

When the required amount of water has been discharged, the valve 38 is closed as well as the valve 37, if the reservoir requires replenishment. For replenishment, the valve 41 is opened and

to permit this water supply, which is under pressure, to fill the reservoir to the desired degree, the vent valve 43 is opened. The timing of the opening of these two valves may be such the pressure on the reservoir 28 may be relieved prior to water supply thereto by venting through line 25 by opening valve 43 before the valve 41 is opened. As stated, valve 41 and valve 43 may be closed simultaneously. Following such closing of the valve 37 is opened whenever preheating of the water in the reservoir is desired.

It will be quite apparent that after the boiler has once generated steam under pressure, the vent 35 must be kept closed to retain boiler pressure whenever valve 37 and/or valve 38 is opened. Should valve 43 be opened while valve 37 is opened, steam will escape without functioning. Should valve 38 be opened while valve 43 be opened and valve 37 be closed, boiler pressure will be sufficient to force the water in a reverse direction through conduit 27, fill the reservoir and then discharge this water from the vent 35. To prevent this, a check valve may be incorporated, if desired, in line 27. The same is not necessary in the cyclic arrangement previously described, as the preferred method of boiler operation.

It will be recalled that a float switch has been described previously in describing the appurtenances applied to the boiler. From what has gone before, it is obvious that the system may be entirely manually controlled and this float switch arrangement is unnecessary. In the preferred form of the invention, however, the system is automatically controlled and boiler supply replenishment is controlled automatically and as illustrated in Fig. 1, by the float switch arrangement, although other automatic controls may be substituted therefor.

When there is an automatic control arrangement, it is to be understood the several valves 37, 39, 41 and 43 are all brought to a common location and these several valves are normally constrained to closed position and have exposed stems, each of which is preferably cam operable either directly or indirectly as by a rocker arm interposed between the proper cam and the associated stem.

A motor, the circuit of which is controlled by lines 18 and 19, secures rotation of the cam shaft having the several cooperating cams thereon for actuating the several valve stems to open the several valves at the predetermined time in the cycle and hold the same open the predetermined interval as required.

This represents the simplest form of automatic control and assumes that for each operation of valve 41 there will be a corresponding operation of valve 39 and the same amount of water supplied to the reservoir will be supplied to the boiler. When, however, the amount of water supplied to the reservoir at each opening of the valve 41 is greater than the amount of water supplied to the boiler upon opening valve 39, then the valve 39 is actuated a plurality of times for each actuation or opening of the valve 41. Thus, a single cam actuation for the rotation of the cam shaft will be provided for and a single corresponding cam will simultaneously, as it were, open the valve 43 and the valves 37 and 38 will remain closed during the period these two valves are simultaneously open. During all the remaining interval the valve 37 will remain open. However, the valve 38 may be opened a plurality of times for each operation of the

other valves as required by the boiler requirements if the plural opening of valve 39 is employed.

It also will be understood that while a so-called motor and cam embodiment of automatic control is illustrated in the drawings and will be now more specifically described, that the invention readily lends itself to the utilization of solenoid operable valves of the quick opening and quick closing type so that the same may be electrically connected with the result that they are electrically interlocked so as to properly function in proper time cycle relationship and the valve 38 is actuated as many times per cycle or but a single time per cycle of operation of the valve 41, as the boiler required replenishment.

In Fig. 2, the numeral 50 indicates a header to which the several lines 27, 26, 33 and 35 connect. The header is interposed therein and is of multi-chamber character as diagrammatically indicated at 51.

In Fig. 3 the header is indicated by the numeral 50, the valve stem by numeral 52, the spring holding the valve open by numeral 53 and the bearing or head portion of the stem by numeral 54. Positioned thereabove is rocker arm 55 pivoted at 56 and constrained upwardly as by spring 57. Adjacent the parallel rocker arms 55 is cam shaft 58 having the cam portions 59 thereon. When the proper cam portion engages the adjacent rocker arm, the associated valve stem is depressed opening the valve in the chamber 51 for fluid flow through that chamber of the header.

A motor, not shown in Figs. 2 and 3, provided with reduction gearing rotates cam shaft 58. The motor circuit is controlled by switch 16-17 either directly or remotely as will be understood in motor control art. If remotely controlled, this float operable switch closes a circuit through an electrically operated switch included in series with the motor. If directly controlled, switch 16-17 is in series with the motor.

Fig. 4 indicates a time cycle chart of operations for the several valves. The broken portions below the dotted line designated by 39' indicate an optional operation of valve 39 when the same operates a plurality of times per total cycle. The heavy lines indicate the valve-open condition for the respectively designated valves.

In Figs. 5 and 6 there is illustrated an electric type of control. The header 150 includes for each chamber 151 a normally closed valve having stem 152 and spring 153 bearing on head 154 normally constraining the valve to closed position. A solenoid 155 when energized is arranged to open the valve in opposition to the spring. A drum controller 158 includes thereon a contact segment 159. Adjacent the plane of rotation of said segment is contact finger 160.

A contact segment 161 (a ring) is contacted by finger 162. Line 163 thereto thus supplies current to the drum. A line 164 from each control finger 160 transmits current from the drum by way of the segment 159 to the proper solenoid or coil. A line 165 connects all the other terminals of said solenoids to the other side of the supply mains.

In Fig. 5, the numeral 170 indicates a motor, 171 a reduction drive for the drum controller and 172-173 the mains to the motor, one of which is interrupted at 174-175 bridgeable by contact 176 operated by solenoid 177 included in the float switch 18-19 circuit.

When the boiler calls for water, the float

switch is closed which closes the motor controlling solenoid switch. Upon motor operation, the drum controller supplies in cyclic relation energy to the several valve solenoids.

5 As illustrated in Fig. 5 and indicated by dotted line 190 and spaced segments 191 and finger 192, one valve may be repetitiously operated for one revolution of the drum controller.

10 The cam shaft and controller-solenoid valve control arrangements are broadly equivalents and either may or may not utilize the header arrangement disclosed.

15 It is to be observed that, controller arrangement while slightly more expensive as original equipment, will be least expensive if the system has to be adjusted as boiler requirements vary incident to an increase or decrease in boiler load resulting from the connection thereto of another steam consuming device or disconnection thereof.

20 The only expense incident to controller modification is grinding off at either or both ends a part of the circuit segment 159 or replacing one with a slightly longer segment. For cam shaft control variation an entirely new cam shaft must be provided, or the old one reground for reductions, or shoes added and reground for additions.

25 In Figs. 7 and 8, there is illustrated two forms of automatic control for the motor driving the reduction gear which rotates the controller or the cam shaft.

30 In Fig. 7, shaft 258 carries a wheel 260 having a recess 261 in its periphery. Adjacent thereto at 262 there is pivoted an arm 263 mounting follower 264 that rides the periphery of wheel 260. Clips 265 mount a mercury switch 266 having terminals 267 and 268 therein. Terminal 267 is connected to float switch line 18. Line 269 connects to the motor or motor controlling relay as previously described.

35 A line 270 with normally open manually operable push button switch 271 therein is in parallel with the float switch. Thus, the motor may be started at will by the operator, the push button being located where most convenient, or duplicated at a plurality of locations as desired, all push buttons being in multiple.

40 After the motor has started, it revolves shaft 258 so that the follower 264 leaves the recess 261 and rides the periphery until it again seats in recess 261 breaking the motor circuit after one cycle of operation.

45 This motor circuit is thus held closed by the periphery tilted mercury switch. When the switch is reversely tilted to open circuit position by roller 264 dropping into recess 261, the rotation of the cam shaft or drum controller ceases. No further rotation occurs until the float switch closes the circuit or the operator closes the manual switch 271.

50 In Fig. 8 numerals of the three hundred series similar to those of the 200 series employed in Fig. 7 indicate like or similar parts. The only difference herein is that the periphery of wheel 360 includes a plurality of recesses 361 suitably spaced apart. These recesses correspond to the motor stopping after valve 39 has been once opened and closed, and represent the stoppage position of the motor after each step-by-step movement of the cam shaft or drum controller has been effected for repetitious opening of valve 39 per cycle of system operation.

55 In this instance, either the float switch or the push button switch can energize the motor to

start wheel rotation until the motor circuit maintaining mercury switch again opens the motor circuit or the motor control circuit if the system is of remote control character.

Wheels 260 and 360 have the same rate of rotation as the drum controller or cam shaft.

It is quite obvious that the float operable switch 16-17 may be of mercoid type whenever desired or required. This prevents arcing, particularly dangerous when the device is utilized in a cleaning establishment where fumes may be of explosive character. Likewise each push button switch may be of mercoid switch type for the same reason, to wit, safety protection.

In Fig. 9 there is illustrated a modified form of float operable switch which readily lends itself to variable water level adjustment without requiring access interiorly of the boiler for float adjustment, and which does not require external adjustment of an external switch and one wherein in the problem of sealing against water and steam leakage is minimized.

In said Fig. 9 the boiler wall 600 is tapped at 601 to sealingly receive a fitting 602 to the interior end of which is suitably secured a somewhat rigid but still flexible steam hose section 603, the other end of which is secured to a similar but reversely positioned fixture 604, the stub of which threads into a closed chamber structure 605.

Thus, the interior of the chamber does not communicate with the boiler interior although the arrangement is mounted interiorly of the boiler. In said chamber is mercury switch 606 and wires 607 thereto are passed into the chamber as shown.

A float 609 includes stem 610 threadedly connected to chamber structure 605 at 610 as shown. The several joints of the interconnected tubular members and joint 601 are of leakproof character.

In the side of the boiler 600 is an opening 611 adjacent joint 601 and a leakproof seal 612 therein of conventional type supports portion 613 but permits turning thereof. A radial arm extension 614 terminates in a handle portion 615. The boiler on its adjacent external face may have serrations, teeth, etc., 616, which cooperate with arm 614 to retain same in adjusted angular position. The opposite end of portion 613 includes 50 the radial interior arm 617 terminating in portion 618 positioned adjacent hose 603 and upon which the latter bears.

As the water level falls in the boiler, the float 609 follows and the hose is the hinge, the portion 618 serving as the pivot or fulcrum. Now, as the handle 615 is moved clockwise or anticlockwise support portion 618 lowers or elevates, respectively, thus raising or lowering the position of the fulcrum as well as moving same outwardly from 60 or inwardly toward fixture 602.

In this manner water level control is adjusted. Water level usual control operation thus is effected other than through a packing structure, and, of course, the switch per se requires no adjustment.

This float operable switch may be substituted for that conventionally illustrated in Fig. 1.

While the invention has been illustrated and described in great detail in the drawings and 70 foregoing description, the same is to be considered as illustrative and not restrictive in character.

The several modifications described herein as well as others which will readily suggest them- 75

selves to persons skilled in this art, all are considered to be within the broad scope of the invention, reference being had to the appended claims.

5 The invention claimed is:

1. In a boiler and supply arrangement, the combination with a boiler and a source of heat therefor for forming steam therein, of an auxiliary reservoir having a drain to the boiler, a pressure line subject to boiler pressure and connected to the reservoir, a vent from said reservoir, a pressure water supply to the reservoir, individual valve means for the drain, pressure line, vent and supply, and means automatically controlling all of said valve means operation, each of said valve means being of normally closed character and constrained toward closed position and the automatic controlling means including a single rotatable controlling element for insuring operation of the respective valves and to open position and for a predetermined interval and in opposition to the constraint.

2. In a boiler and supply arrangement, the combination with a boiler and a source of heat therefor for forming steam therein, of an auxiliary reservoir having a drain to the boiler, a pressure line subject to boiler pressure and connected to the reservoir, a vent from said reservoir, a pressure water supply to the reservoir, individual valve means for the drain, pressure line, vent and supply, and means automatically controlling all of said valve means operation, each of said valve means being of normally closed character and constrained toward closed position and the automatic controlling means including a single rotatable controlling element for insuring operation of the respective valves and to open position and for a predetermined interval and in opposition to the constraint, the single controlling rotatable element being of the electric controller switch type.

3. In a boiler and supply arrangement, the combination with a boiler and a source of heat therefor for forming steam therein, of an auxiliary reservoir having a drain to the boiler, a pressure line subject to boiler pressure and connected to the reservoir, a vent from said reservoir, a pressure water supply to the reservoir, individual valve means for the drain, pressure line, vent and supply, and means automatically controlling all of said valve means operation, each of said valve means being of normally closed character and constrained toward closed position and the automatic controlling means including a single rotatable controlling element for insuring operation of the respective valves and to open position and for a predetermined interval and in opposition to the constraint, the single controlling rotatable element being of cam shaft type.

4. In a boiler and supply arrangement, the combination with a boiler and a source of heat therefor for forming steam therein, of an auxiliary reservoir having a drain to the boiler, a pressure line subject to boiler pressure and connected to the reservoir, a vent from said reservoir, a pressure water supply to the reservoir, individual valve means for the drain, pressure line, vent and supply, and means automatically controlling all of said valve means operation, each of said valve means being of normally closed character and constrained toward closed position and the automatic controlling means including a single rotatable controlling element for insuring operation of the respective valves

and to open position and for a predetermined interval and in opposition to the constraint, a cam member rotatable in timed relation with the single rotatable element, a motor for rotating the latter and the cam member, switch means for initiating motor operation, and other switch means operable by said cam member for maintaining motor operation for the desired interval and then discontinuing the motor operation.

5. In a boiler and supply arrangement, the combination with a boiler and a source of heat therefor for forming steam therein, of an auxiliary reservoir having a drain to the boiler, a pressure line subject to boiler pressure and connected to the reservoir, a vent from said reservoir, a pressure water supply to the reservoir, individual valve means for the drain, pressure line, vent and supply, and means automatically controlling all of said valve means operation, each of said valve means being of normally closed character and constrained toward closed position and the automatic controlling means including a single rotatable controlling element for insuring operation of the respective valves and to open position and for a predetermined interval and in opposition to the constraint, a cam member rotatable in timed relation with the single rotatable element, a motor for rotating the latter and the cam member, switch means for initiating motor operation, and other switch means operable by said cam member for maintaining motor operation for the desired interval and then discontinuing the motor operation, the cam member and other switch means association being of repetitious motor operation character for each rotation of the cam member.

6. In a boiler and supply arrangement, the combination with a boiler and a source of heat therefor for forming steam therein, of an auxiliary reservoir having a drain to the boiler, a pressure line subject to boiler pressure and connected to the reservoir, a vent from said reservoir, a pressure water supply to the reservoir, individual valve means for the drain, pressure line, vent and supply, and means automatically controlling all of said valve means operation, each of said valve means being of normally closed character and constrained toward closed position and the automatic controlling means including a single rotatable controlling element for insuring operation of the respective valves and to open position and for a predetermined interval and in opposition to the constraint, a cam member rotatable in timed relation with the single rotatable element, a motor for rotating the latter and the cam member, boiler water level responsive, switch means for initiating motor operation, and other switch means operable by said cam member for maintaining motor operation for the desired interval and then discontinuing the motor operation.

7. In a boiler and supply arrangement, the combination with a boiler and a source of heat therefor for forming steam therein, of an auxiliary reservoir having a drain to the boiler, a pressure line subject to boiler pressure and connected to the reservoir, a vent from said reservoir, a pressure water supply to the reservoir, individual valve means for the drain, pressure line, vent and supply, and means automatically controlling all of said valve means operation, each of said valve means being of normally closed character and constrained toward closed position and the automatic controlling means including a single rotatable controlling element

for insuring operation of the respective valves to open position and for a predetermined interval and in opposition to the constraint, a cam member rotatable in timed relation with the single rotatable element, a motor for rotating the latter and the cam member, boiler water level responsive, switch means for initiating motor operation, and other switch means operable by said cam member for maintaining motor operation for the desired interval and then discontinuing the motor operation, the cam member and other switch means association being of repetitious motor operation character for each rotation of the cam member.

15. 8. In a boiler and supply arrangement, the combination with a boiler and a source of heat therefor for forming steam therein, of an auxiliary reservoir having a drain to the boiler, a pressure line subject to boiler pressure and connected to the reservoir, a vent from said reservoir, a pressure water supply to the reservoir, individual valve means for the drain, pressure line, vent and supply, and means automatically controlling all of said valve means operation, each of said valve means being of normally closed character and constrained toward closed position and the automatic controlling means including a single rotatable controlling element for insuring operation of the respective valves and to open position and for a predetermined interval and in opposition to the constraint, a cam member rotatable in timed relation with the single rotatable element, a motor for rotating the latter and the cam member, manually operable switch means for initiating motor operation, and other switch means operable by said cam member for maintaining motor operation for the desired interval and then discontinuing the motor operation.

45. 9. In a boiler and supply arrangement, the combination with a boiler and a source of heat therefor for forming steam therein, of an auxiliary reservoir having a drain to the boiler, a pressure line subject to boiler pressure and connected to the reservoir, a vent from said reservoir, a pressure water supply to the reservoir, individual valve means for the drain, pressure line, vent and supply, and means automatically controlling all of said valve means operation, each of said valve means being of normally closed character and constrained toward closed position and the automatic controlling means including a single rotatable controlling element for insuring operation of the respective valves and to open position and for a predetermined interval and in opposition to the constraint, a cam member rotatable in timed relation with the single rotatable element, a motor for rotating the latter and the cam member, manually operable switch means for initiating motor operation, and other switch means operable by said cam member for maintaining motor operation for the desired interval and then discontinuing the motor operation.

60. 10. In a boiler and supply arrangement, the combination with a boiler and a source of heat therefor for forming steam therein, of an auxiliary reservoir having a drain to the boiler, a pressure line subject to boiler pressure and connected to the reservoir, a vent from said reservoir, a pressure water supply to the reservoir, individual valve means for the drain, pressure

line, vent and supply, and means automatically controlling all of said valve means operation, each of said valve means being of normally closed character and constrained toward closed position and the automatic controlling means including a single rotatable controlling element for insuring operation of the respective valves and to open position and for a predetermined interval and in opposition to the constraint, a cam member rotatable in timed relation with the single rotatable element, a motor for rotating the latter and the cam member, boiler level responsive switch means for initiating motor operation, manually operable switch means in parallel therewith for a like purpose, and other switch means operable by said cam member for maintaining motor operation for the desired interval and then discontinuing the motor operation.

11. In a boiler and supply arrangement, the combination with a boiler and a source of heat therefor for forming steam therein, of an auxiliary reservoir having a drain to the boiler, a pressure line subject to boiler pressure and connected to the reservoir, a vent from said reservoir, a pressure water supply to the reservoir, individual valve means for the drain, pressure line, vent and supply, and means automatically controlling all of said valve means operation, each of said valve means being of normally closed character and constrained toward closed position and the automatic controlling means including a single rotatable controlling element for insuring operation of the respective valves and to open position and for a predetermined interval and in opposition to the constraint, a cam member rotatable in timed relation with the single rotatable element, a motor for rotating the latter and the cam member, boiler level responsive switch means for initiating motor operation, manually operable switch means in parallel therewith for a like purpose, and other switch means operable by said cam member for maintaining motor operation for the desired interval and then discontinuing the motor operation, the cam member and said other switch means association being of repetitious motor operation character for each rotation of the cam member.

12. In a boiler and supply arrangement, the combination with a boiler and a source of heat

therefor for forming steam therein, of an auxiliary reservoir having a drain to the boiler, a pressure line subject to boiler pressure and connected to the reservoir, a vent from said reservoir, a pressure water supply to the reservoir, individual valve means for the drain, pressure line, vent and supply, and means automatically controlling all of said valve means operation, each of said valve means being of normally closed character and constrained toward closed valve position and the automatic controlling means including a single rotatable controlling element for insuring operation of the respective valves and to the open position and maintenance therein for a predetermined interval and in opposition to the constraint, the single controlling rotatable element being of cam shaft type and having appropriate cam means thereon, and individual rocker arm means associated with each valve means and juxtaposed adjacent the appropriate cam means for operation thereby.

13. In a boiler and supply arrangement, the combination with a boiler and a source of heat therefor for forming steam therein, of an auxiliary reservoir having a drain to the boiler, a pressure line subject to boiler pressure and connected to the reservoir, a vent from said reservoir, a pressure water supply to the reservoir, individual valve means for the drain, pressure line, vent and supply, and means automatically controlling all of said valve means operation, each of said valve means being of normally closed character and constrained toward closed valve position and the automatic controlling means including a single rotatable controlling element for insuring operation of the respective valves and to the open position and maintenance therein for a predetermined interval and in opposition to the constraint, the single controlling rotatable element being of drum controller type and having appropriate contact segments thereon, individual coil means associated with each valve means, and individual switch contacts for each coil means and juxtaposed relative to the segments on the controller for selective engagement by said segments for selective coil means energization.

HARRY D. FORSE.
